(57) **CLAIM**

The ornamental design for a label for a package surface, as shown and described.

DESCRIPTION

The patent or application file contains at least one drawing executed in color. Copies of this patent or patent application publication with color drawing will be provided by the Office upon request and payment of the necessary fee.

FIG. 1 is a view of a first embodiment of a label for a package surface; and,

FIG. 2 is a view of a second embodiment of a label for a package surface.

The broken lines in the figures define boundaries of the claimed design and form no part of the claimed design.
